UNITED STATES PATENT OFFICE.

ELI J. GAGNON, OF EXETER, NEW HAMPSHIRE.

EDGE-SETTING MACHINE.

1,277,402.

Specification of Letters Patent. Patented Sept. 3, 1918.

Application filed November 14, 1916. Serial No. 131,330.

To all whom it may concern:

Be it known that I, ELI J. GAGNON, a citizen of the United States, residing at Exeter, county of Rockingham, State of New Hampshire, have invented certain new and useful Improvements in Edge-Setting Machines, of which the following is a specification.

This invention relates to improvements in edge setting machines adapted to burnish the edges of the shank and tread of a shoe sole. Such machines usually consist of a vibrating tool head provided with oppositely disposed tool posts upon which the different tools for operating upon portions of the sole edge of differing contours and thickness are adapted to be interchangeably mounted. The setting of the edge of a shoe sole usually involves two consecutive operations and the use of two different sizes and styles of setting tools.

In operating upon the tread portion of the sole edge, the particular tool best adapted for this work is affixed in the twin post tool head and is caused to vibrate against the sole edge by the vibrating mechanism of the machine, and during its vibration the operative guides the sole edge continuously past the setting tool until he reaches the narrowed inwardly curved portion of the shank of the sole. It is then necessary to revolve the tool head through half a revolution to throw out of operative position the setting tool which had been operating upon the edge of the tread portion of the sole and to throw into operative position the theretofore idle setting tool of the other tool post and which tool is designed and best adapted for setting the edge of the shank portion. In order to turn the tool head of the usual edge setting machine, it has been necessary for the operative to place one hand over the exposed upper end of the tool head and manually turn it against the resistance of a coiled spring, thereby to throw out of position the one tool and to throw into position the other tool. This required the removal of one hand of the operative from the shoe sole and was a source of inconvenience not only as regards the actual turning of the tool post itself, but as regards the matter of supporting the shoe and maintaining it in proper position to be worked upon by the shank or tread setting tool when said tool was swung into operative position. Owing to the high

speed at which these machines are required to operate, and the difficulty of manually rotating the tool head itself, the operative is usually obliged to put down the shoe while turning the tool head to its new position. This involves a delay and momentarily distracts the operative's attention from the operation of setting the sole edge and a corresponding loss of efficiency. Although special edge setting machines have been designed in which it has been possible to turn the tool head without removing the hand from the shoe, such machines so far as I am aware have not found favor in the trade and have not been generally adopted.

It is the object of the present invention to provide a convenient and readily operable mechanism for revolving the tool head from one of its operative positions to the other which will leave free the hands of the operative to support and guide the sole during the operation of changing the position of the tool head. This object is secured in my present invention by providing a tool shifting device capable of operation by a simple motion which may be imparted by a treadle or the like. My device is essentially an attachment for the usual edge setting machine and may be attached to practically any edge setting machine upon the market without substantial reorganization or modification of the construction and operation of such machines, and in this respect differs essentially from those machines in which this feature of shifting the tool head by means which leave free the operator's hands has been included only through a substantial reorganization and modification of the machine itself. In carrying out my invention the tool is given a reciprocatory motion preferably through the instrumentality of a treadle actuated bar and this motion is transmitted as rotary motion applied to the tool spindle by a suitable motion transmitting means, whereby to positively and quickly revolve the tool head through a half revolution.

An illustrative embodiment and the operation thereof in accordance with my invention is fully disclosed in the specification which follows. In the drawings accompanying that specification, I have shown an embodiment of my invention which has been found satisfactory in use and adapted for practical operation in standard edge setting machines. Throughout this specifica-

tion and in the drawings, like reference characters are correspondingly applied: In the drawings:—

Figure 1 is a partial side view of an edge setting machine of standard construction equipped with my invention.

Figs. 2 and 3 are elevations of a tool head in accordance with my invention, removed from the machine, and showing different 10 positions of the tool posts.

Fig. 4 is a partial central section through the tool head and showing position of the parts in shifting the tool post.

Fig. 5 is a similar section at right angles 15 to Fig. 4 and showing the tool post locked in its carrier.

Fig. 6 is a detail view illustrating the mount for the tool head shifting device, and

Fig. 7 is a detail view of a part herein- 20 after described.

For the purposes of illustration, I have shown in Fig. 1 a sufficient portion of an edge setting machine of standard construction equipped with my improvement to enable the operation of my invention to be 25 readily understood. It will of course be understood that my improvement is applicable to either single or twin edge setting machines.

30 I have indicated generally at 1 the frame of an edge setting machine and at 2 the bed of the head structure. Mounted on one or both ends of the bed plate 2, according to the type of machine, is a vibratory tool 35 head indicated generally at 3. The specific manner of mounting the tool head on the bed and the specific mechanism for vibrating it form no part of the present invention and are not therefore shown or de- 40 scribed in detail herein.

The tool head itself consists of an axial spindle 4 to the lower end of which is fixed in any suitable manner a twin post tool member 5 having diverging tool posts 6 with 45 tool retaining springs or the equivalent devices 7, whereby to detachably support the different edge setting tools. Surrounding the spindle 4 and spaced therefrom is a sleeve 8 terminating at its lower end in a 50 bifurcated portion 9 adapted to normally straddle the sides of the member 5. Set through one of the overhanging sides of the portion 9 is a stud or equivalent device 10 adapted to fit in a groove 11 cut in a sleeve 55 12 fixed to the spindle 4 between it and the sleeve 8. The groove is substantially of double Y-form, the Y portions being cut at opposite sides of the spindle, and the upper ends of their forks merging into each 60 other so that there is a continuous annular space above the straight depending portions thereof. The spindle is fixed near its upper end in a cap sleeve 13 which is partially received in the sleeve 8. The upper end of 65 the spindle itself is exposed beyond the

sleeve 13 for depression by a treadle actuated bar 14 which is fastened in a mount 15 adjustably secured to the bed 2 and connected by a link 16 to a spring tensioned treadle 17 disposed at the base of the machine convenient to the operator's foot. The mount 15 as here shown consists of a plate or bracket member 151 provided with spaced ears 152 between which the edge of the bed plate 2 of the machine is received and secured by a bolt or other fastening. The plate 151 is provided at each end with bolts 153 which slide in slots 154 formed in the downwardly extending portion 155 of the bar 14. The link 16 of the treadle is fastened to the portion 155, and the spring 156 for the treadle is fastened at its lower end to the treadle and at its upper end to a hook 157 carried by the bracket 151—see Figs. 1 and 6. The downward movement 85 of the spindle 4 and sleeve 13 is yieldingly opposed and the parts automatically returned to normal position by a coil spring 18 confined between the cap sleeve 13 and an internal perforated web 19 formed on the sleeve 8 and through which the spindle passes and is guided.

Surrounding the sleeve 8 and adjustable circumferentially thereon through a screw 20 and slot 21 is a covering sleeve 22 which 95 is provided at its upper portion with a cut-out developed on a curve to provide a curved guiding edge 23 for the free end of a blade spring or equivalent device 24, fastened to the upper exposed end of the cap sleeve 13. 100 The purpose of this construction is to positively start the tool head in the direction in which it is to turn when the treadle is depressed.

The operation of my device is as follows: 105 With the tool head in position shown in Fig. 2, a depression of the treadle will cause the spindle and with it the tool post member and sleeve 12 to move downward as shown in Fig. 3 and in this movement to turn through an arc of 180° whereby to bring into effective position relative to the sole edge that tool post 6 which in the Fig. 2 position of the parts is disposed in ineffective position. The actual transmission of the reciprocatory 110 motion of the spindle 4 as rotary motion applied to the tool post member and the consequent rotation of the tool post member 5 is effected through the engagement of the stud 10 with the groove 11 as the sleeve 12 115 containing the groove is carried downward with the spindle past the fixed stud. When the spindle reaches the limit of its downward movement, the coil spring 18 returns it and the parts moving with it to their normal 120 positions, but the tool post member 5 has of course been turned to its new position.

By my invention the operative is enabled to turn the tool post to a new position according to the portion of the sole edge he 130

wishes to work upon without removing his hands from the shoe and without loss of time or attention to the setting operation itself, and consequently without loss of efficiency.

My improvement is capable of ready application to edge setting machines now in use and indeed my invention may be embodied in the tool heads themselves of such 10 machines.

Various modifications in the form and construction of my invention may obviously be resorted to if within the limits of the appended claims.

15 What I therefore claim and desire to secure by Letters Patent is:

1. In an edge setting machine, a reciprocable and rotatable tool head, means operable without requiring the removal of the 20 operative's hand from the work for reciprocating and rotating said tool head, a guide member carried by said tool head, and a curved guiding edge mounted to coöperate with said guide member to positively start 25 the tool head to rotate in the proper direction.

2. In an edge setting machine, a rotatable tool head, treadle-operated means for rotating said head, and a movable guide device 30 and a fixed guiding edge arranged in co-operative relation for positively compelling the tool head to start to rotate in the desired direction.

3. In an edge setting machine, a reciprocable and rotatable tool head having a 35 groove, treadle-actuated connections for imparting a reciprocatory motion in one direction to said head, a spring yieldingly opposing said motion, and a stud coöperating with said groove for transmitting said reciprocatory motion as rotary motion applied to the tool head to rotate said head through an arc of approximately 90°.

4. In an edge setting machine, a tool head 45 comprising a reciprocable and rotatable spindle, a sleeve fast thereto having a groove, a twin post tool member on said spindle, a relatively fixed member about said sleeve having a stud disposed for engagement in 50 said groove, a treadle-actuated member adapted to impart a reciprocatory movement to said spindle, and a spring yieldingly opposing said movement.

5. In an edge setting machine, a tool head 55 comprising a reciprocable and rotatable spindle, a sleeve fast thereto having a groove and carrying a twin post tool member, a relatively fixed member about said sleeve having a stud disposed for engagement in 60 said groove, a treadle-actuated member adapted to impart a reciprocatory movement to said spindle, a spring yieldingly opposing said movement, a curved guiding edge fixed relatively to said spindle, and a guide device 65 carried by said spindle and adapted to ride

upon said guiding edge to compel said spindle to start to turn in the proper direction.

6. In an edge setting machine, a reciprocable and rotatable tool head including a spindle, means for imparting a reciprocatory movement to said spindle, means for transmitting said movement as rotary movement applied to the spindle to rotate said spindle, and a movable guide device and a fixed guiding edge arranged in coöperative relation and adapted to positively compel said spindle to start to turn in the desired direction. 75

7. In an edge setting machine, a reciprocable and rotatable tool head including a 80 spindle, means for imparting a reciprocatory movement to said spindle, means for transmitting said movement as rotary movement applied to the spindle to rotate said spindle, a guide carried by the spindle, and 85 a curved guiding edge fixed relatively to said guide and coöperating therewith to positively compel said spindle to start to turn in the desired direction.

8. In an edge setting machine, a tool post, a reciprocable and rotatable spindle fixed thereto and provided with a groove, a fixed member disposed for engagement in said groove, and means to reciprocate said spindle. 90

9. In an edge setting machine, a tool post, a reciprocable and rotatable spindle fixed thereto and provided with a groove, a stud disposed for engagement in said groove, and means to reciprocate said spindle. 95

10. In an edge setting machine, a frame member having a locking recess, a reciprocable and rotatable tool holder partially contained within said recess, means for moving said holder out of said recess, and means fixed upon said frame member and coöperating with said tool holder for rotating said tool holder upon a reciprocation thereof. 105

11. In an edge setting machine, a frame member having a locking recess, a reciprocable and rotatable tool holder partially contained within said recess and provided with a groove, means for moving said holder out of said recess, and means fixed upon said frame member and disposed for engagement in said groove for rotating said tool holder upon a reciprocation thereof. 110

12. In an edge setting machine, a frame member having a locking recess, a reciprocable and rotatable tool holder partially contained within said recess and provided with a groove permitting rotation thereof in either direction, means for moving said holder out of said recess, and a stud fixed upon said frame member and disposed for engagement in said groove for rotating said tool holder upon a reciprocation thereof. 120

13. In an edge setting machine, a frame member, a tool holder arranged to interlock therewith, means for imparting recipro- 125

reciprocatory motion to said tool holder to disengage said holder from said frame member, and a device carried by said frame member and past which said tool holder moves when reciprocated for transmitting said reciprocatory motion as rotary motion applied to the tool holder to change the angular relation of the frame and holder.

14. In an edge setting machine, a frame member, a tool holder arranged to interlock therewith and having a groove, means for imparting reciprocatory motion to said tool holder to disengage said holder from said frame member, and a laterally disposed stud fixed upon said frame member and engaging the groove in said tool holder for transmitting said reciprocatory motion as rotary motion applied to the tool holder to change the angular relation of the frame and holder.

15. In an edge setting machine, a frame member, a tool holder arranged to interlock therewith and provided with a groove, and a stud fixed in said frame member and disposed for engagement in said groove.

16. In combination with a reciprocable and rotatable tool holder of the class described, a member having a guiding edge,

and a guide device carried by said tool holder and having an end effectively disposed in position to ride upon said guiding edge, whereby to cause said tool holder to start to turn in the desired direction upon reciprocation thereof.

17. In combination with a reciprocable and rotatable tool holder of the class described, a member sleeved thereabout and having a curved guiding edge and a yielding guide device carried by said tool holder and having an end effectively disposed in position to ride upon said guiding edge, whereby to cause said tool holder to start to turn in the desired direction upon reciprocation thereof.

18. In combination, a reciprocable and rotatable member, means for imparting reciprocatory motion to said member, and means co-operating with said member to rotate it as it is reciprocated therewith.

In testimony whereof I affix my signature in presence of two witnesses.

ELI J. GAGNON.
